UNITED STATES PATENT OFFICE.

OTTO F. ROHWEDDER, OF DAVENPORT, IOWA.

BREAD-FASTENING APPARATUS.

Application filed January 26, 1928. Serial No. 249,614.

My invention relates to improvements in bread fastening apparatus.

The objects of my invention are to provide a manually operable apparatus for inserting staples lengthwise in a sliced loaf of bread for the purpose of retaining the slices in their original position.

I attain these objects by the means illustrated in the accompanying drawings, in 10 which,—

Figure 1 is a plan view of my apparatus;

Figure 2 is a sectional elevation on the line, 2—2, of Figure 1;

Figure 3 is a cross-section view on the line, 15 3—3, of Figure 1;

Figure 4 is an end elevation.

My apparatus comprises a frame which is preferably a box or inverted U-shaped casting, 1, having flanges, 2 and 2', at the 20 lower edges thereof adapted to secure the frame in suitable guide-ways formed in the take-off apron or table of a bread slicing machine and the base may be secured in adjustable position longitudinally by any of the 25 usual well-known means for that purpose.

The upper face of the frame is provided with a channel, 11, which runs the entire length of the frame and side bars, 3 and 3', are secured to the sides of the frame and 30 project slightly over the channel to form detents which secure in the channel a pusher block, 6.

Sides, 10 and 10', of the channel, 11 are 35 preferably formed at an angle making the channel narrower at the bottom so as to properly center one of the crimped staples, 12, when laid therein. The pusher block, 6, is provided with a handle, 7, for convenience in operation. At the rear of the frame, 1, 40 a pin, 9, is secured which acts as a stop or detent to stop the pusher block, 6, at the rear of its travel. Near the front of the frame, a cross-bar, 4, is secured to the side bars, 3 and 3', or to the frame and a spring plate, 5, is 45 secured to the cross-bar, 4. The spring plate, 5, is mounted at an angle so that the front end of it is on a level with or slightly below the bed of the channel, 11. The purpose of the spring plate, 5, is to form a guiding 50 detent for the staples as they pass out of the channel, 11, into the bread. The spring, 5, is preferably made of light weight material so as not to afford any great resistance to the

passage of the staple or to the extended front end of the pusher block, 6. 55

In the use of my device, a pair of these appliances are slidingly mounted upon the take-off apron of a bread slicing machine at opposite sides of the portion of the apron upon which the sliced loaf of bread is delivered as it comes from the slicing blades. 60

Single staples may be laid in the channels or grooves of each appliance and the pusher blocks are then manually operated toward each other. The staples are preferably 65 formed with a length considerably more than one-half of the loaf and the apparatus described should be of such height that the channel, 11, will be approximately one-half as high as the height of the loaf of bread to 70 be secured.

It is obvious that the size, form and proportions of my appliance and the various parts thereof, may be varied to a considerable extent without departing from the 75 spirit of my invention.

I claim:

1. An appliance for driving staples into a sliced loaf of bread, comprising a frame having a longitudinal channel formed in 80 the upper portion thereof, a pusher block slidingly mounted in the channel, side bars secured upon the edges of the channel and projecting over the channel a short distance, a cross-bar secured upon the side bars near 85 the front end thereof, and a spring plate having its upper end secured upon the cross-bar and sloping downwardly and forwardly with its lower end adjacent the bed of the channel. 90

2. An appliance for driving staples into a sliced loaf of bread, comprising a frame having a longitudinal channel formed in the upper portion thereof, a pusher block 95 slidingly mounted in the channel, side bars secured upon the edges of the channel and projecting over the channel a short distance, a cross-bar secured upon the side bars near the front end thereof, and a spring plate having its upper end secured upon the cross-bar and sloping downwardly and forwardly with its lower end adjacent the front end of the channel. 100

In testimony whereof he affixes his signature.

OTTO F. ROHWEDDER.
